UNITED STATES PATENT OFFICE

THOMAS J. ABBOTT, OF TROY, NEW YORK, ASSIGNOR TO CLUETT, PEABODY & CO., INC.,
OF TROY, NEW YORK, A CORPORATION OF NEW YORK

FOLDING MACHINE

Application filed December 8, 1925. Serial No. 74,030.

This invention pertains to pressing and folding machines of that class employed in the commercial production of collars, relating particularly to means for accurately positioning the blank upon the table in respect to the presser plates for mortise-locking the ends and for uniformly distributing the main folds. It is very important in making the mortise-locks on the collar ends that the blank be accurately positioned on the bed plate in order that when the primary fold is made it will be through the intersecting point of the secondary folds.

The objects of the present invention are to provide means whereby in forming mortise-locks on collars the primary folds will at all times be made in accurate relation to the main or secondary folds; to provide means for correctly positioning the blank on the bed in respect to the folding plates; to provide positioning means attached to the movable folder plates for positioning the blank in respect thereto; to provide an adjustable gauge upon the folder plates; to provide primary folding means conveniently accessible for the operator; to provide a flaring ledge upon the curved portion of the folding plates for uniformly turning the corresponding edge of the blank into a smooth seam; and to provide a device which will be simple in construction and efficient in operation.

In order to attain these objects I have devised abutments mounted upon the movable elements of the folding machine for assuring the correct position of the blank preliminary to the making of the primary and secondary folds. One of these abutments is fixed in position on the movable elements while the other is so attached that it can be angularly or laterally adjusted. Also there is mounted upon the folder plates at the points where the front edges of the collar are curved sloping ledges for distributing the folds uniformly, whereby the main folds along the edges are even and unwrinkled.

One embodiment chosen to illustrate the genus of my invention is shown in the accompanying drawings, in which:—

Fig. 1 is a plan view of the folding machine with parts broken away;

Fig. 2 is a section on line 2—2 of Fig. 1;
Fig. 3 is a view looking at Fig. 2 from the right-hand side;

Fig. 4 is a perspective view of the gauge plate;

Fig. 5 is a fragmentary view of the left-hand edge of the collar blank;

Fig. 6 is a view similar to Fig. 5 but after the fold is made; and

Fig. 7 is a perspective view of the finished collar.

These pressing and folding machines are in general of well-known construction, comprising a frame heated bed 1 mounted in the table, a die supporting arm 2, and folder plates 3 and 4. Ordinarily these two folder plates are practically identical in construction, except that one is adapted to fold the right end of the collar blank, and the other is adapted to fold the left end of the said blank. Each folder plate comprises a thin metal sheet 5 contoured on its inner edges to conform with the corresponding edges of the blank and die. This sheet is secured to the under side of a heavier metal member 6 having a raised overhanging lug 7 slotted at 8 to be adjustably connected with one of the folder bars 9 by means of clamping bolts 10. Some such actuating means as eccentrics 11 engage with the folder bars, whereby the folder plates are oscillated over the table surface in the direction of the arrows. Cleats 12 overlie the folder bars and are bolted to the table to hold the bars from lifting but allowing free sliding movement.

The points of the collar blank at the junction of the front and bottom edges are mortise-locked by means of primary folding claws 13 pivoted to plates 6 and actuated by heat insulating handles 14 extending laterally to points where they are readily accessible to the operator, each claw being automatically returned to normal inoperative position by a tension spring 15, all as described in copending application of Sanford L. Cluett filed on even date herewith.

In order to position the collar blank upon the table in respect to the folder plate an abutment 16 is riveted to the plate to abut against the bottom edge of the collar and a

gauge 17 is also attached thereto to abut against the top edge of the blank. For the purpose of positioning these abutments for collars of varying sizes, the gauge is adjustably connected to the plate by having formed therein an elongate slot 18 cooperating with clamp bolt 19 to permit angular or lateral adjustment. One end of the gauge is turned to provide a flange 20 for seating thereon a face plate 21, these being movable relatively to each other by rivets 22 on one member engaging and sliding in vertically elongated slots 23 formed in the other member.

A certain style of collar provides a greater space for the tie and accessibility to the collar button, and such a style is made by cutting away a portion of the blank on the front edge of the blank between the bottom edge and the top edges. At the top of the cut there will be formed a curved edge 24 which when the margin 25 is folded will buckle unless at the same time this edge is spread out uniformly. Provision is made for properly folding the curved portion during the same operation which folds the marginal edge 25 by fixing at this point on the folder plate a raised ledge 26, decreasingly flared toward its ends. As the folder plate carrying this ledge moves over the marginal edge to form the main folds it spreads this curved portion out evenly, thereby causing a uniform and even edge fold to be made.

It will be understood from the above description that these positioning elements will be similarly placed upon the left folder plate, and that they will function in a like manner to fold the left edge of the collar blank.

In the operation of the device the collar blank is inserted between the two folding plates and positioned by the abutment 16 and gauge 17 carried by each folding plate. The curved front edge 24 of the blank will be positioned adjacent to the curved flared ledge 26 on the folder plates and when said plates are actuated by the cams this ledge tends to distribute the marginal edge 25 into an even and uniform fold. This is due to the fact that the marginal portion 25 of the collar (Fig. 5) rests on the rounded ledge 26 when the collar is placed in position on the bed plate and when the body of the collar is clamped down by the die plate on arm 2 this ledge holds the concave margin 25 of the collar in a raised position, the margin inclining upwardly from the broken line in Fig. 5 to the free edge of the margin and curving over the ledge in a direction parallel to the edge. Thus the concave margin assumes a shape somewhat like a section of a conical surface. With the concave margin in this position its fullness is distributed along the margin in successive uniform minute pleats or ripples when the margin is folded over the die plate by the folding plate carrying the ledge 26, instead of causing the

fullness to bunch up in random folds as would occur in the absence of ledge 26.

It is understood that the invention is not limited to the details of construction herein described, but that various changes may be made therein such as may occur to those familiar with the art, without departing from the spirit of the invention.

I claim:

1. A folding machine for making mortise-lock folds having a primary fold at a corner of the article and curved secondary folds along at least one of the edges meeting at the corner, the machine having a bed, a presser movable toward and from the bed, means for making a primary fold at the corner of the article, and folder plates movable over the bed to form the secondary folds, abutments on the said plates for positioning the article, and a ledge on one of said folder plates for distributing the fullness along one of the curved secondary folds. 75

2. A folding machine for making mortise-lock folds having a primary fold at a corner of the article and curved secondary folds along at least one of the edges meeting at the corner, the machine having a bed, a presser movable toward and from the bed, means for making a primary fold at the corner of the article, and folder plates movable over the bed to form the secondary folds, abutments on the said plates for positioning the article, and a flared shoulder on the plates for distributing the fullness evenly along the curved secondary folds. 90

3. A folding machine for making mortise-lock folds having a primary fold at a corner of the article and curved secondary folds along at least one of the edges meeting at the corner, the machine having a bed, a presser movable toward and from the bed, means for making a primary fold at the corner of the article, and folder plates movable over the bed to form the secondary folds, and a shoulder on said plates for causing one of the curved secondary folds to be evenly turned by evenly distributing the fullness along the fold. 105

4. A folding machine for making mortise-lock folds having a primary fold at a corner of the article and curved secondary folds along at least one of the edges meeting at the corner, the machine having a bed, a presser movable toward and from the bed, means for making a primary fold at the corner of the article, and folder plates movable over the bed to form the secondary folds, and a sloping ledge on said plates for causing one of the curved secondary folds to be evenly turned by evenly distributing the fullness along the fold. 115

5. A folding machine for making mortise-lock folds having a primary fold at a corner of the article and secondary folds along the edges meeting at the corner, the machine 130

having a bed, a presser movable toward and from the bed, and folder plates movable thereover to form the secondary folds, positioning abutments on the folder plates for the article, and a claw movably connected to the plates for forming the primary fold, said claw having a handle extending laterally therefrom.

6. A folding machine for making mortise-lock folds having a primary fold at a corner of the article and secondary folds along the edges meeting at the corner, the machine having a bed, a presser movable toward and from the bed, and folder plates movable thereover to form the secondary folds, positioning abutments on the folder plates for the article, and a claw movably connected to the plates for forming the primary fold, said claw having a heat insulation handle extending laterally therefrom.

Signed by me at Troy, New York, this 27th day of November, 1925.

THOMAS J. ABBOTT.
